UNITED STATES PATENT OFFICE.

JACOB CASPAR VOLLMAR, OF PORT HURON, MICHIGAN, ASSIGNOR OF TWO.
FIFTHS TO GEORGE FRANK, OF SAME PLACE.

SUSPENDERS.

SPECIFICATION forming part of Letters Patent No. 502,792, dated August 8, 1893.

Application filed April 16, 1892. Serial No. 429,439. (No model.)

To all whom it may concern:

Be it known that I, JACOB CASPAR VOLLMAR, a citizen of the United States, residing at Port Huron, in the county of St. Clair and State of Michigan, have invented certain new and useful Improvements in Suspenders, of which the following is a specification, reference being had therein to the accompanying drawings.

10 This invention relates to a new and useful improvement in suspenders, and it consists in the construction and arrangement of parts hereinafter described and definitely pointed out in the claims.

15 In the drawings, Figure 1 is an elevation of a suspender embodying my invention. Fig. 2 is a detached perspective view of the buckle guard or cover. Fig. 3 is a detached perspective view showing the under side of the button and strap guard. Fig. 4 is a rear elevation of the button guard showing a modified form thereof.

20 While I have shown my device as applied to a suspender it is evident that there are various other uses to which it may be put and I do not desire to limit myself to that particular use.

25 A is the web of the suspenders, B is the buckle having a spring jaw C at its lower end in which the eye D of the upper end of the straps E is adapted to engage. These straps E are provided at their lower ends with the usual button holes F.

30 It is found in the use of suspenders that the garments of the wearer opposite the buckles and buttons are usually badly worn. To overcome this objection I form a guard or cover for the buckles and buttons. To this end I form the buckle cover by means of a sleeve G 35 preferably of leather, or similar flexible material, having an elastic section H extending longitudinally thereof, at one side this sleeve being of sufficient size to embrace the web A of the suspender and slide freely thereon and also 40 to embrace the buckle B when slid down in

the position shown in dotted lines in Fig. 1. In this position the elastic section H is slightly extended so that it is held in its adjusted position against probability of accidental displacement.

45 H' is a flap preferably of triangular shape, as shown in Fig. 3 and having a strap I at its upper edge adapted to engage in the eye D and be secured thereto in any suitable manner. This flap is of such size as to cover the straps E in the position in which they are in use and is provided on its inner edge with a guide strip J, under which the straps E pass, preventing the displacement of the straps from the guard flap, at the same time allowing access to the button-holes in the ends of the straps. In this way all the wear due to the motion of the person and caused by the presence of the buckles and buttons is taken up in the sleeve and flap H' and the cloth 55 fully protected.

50 It is evident that the buckle cover may be applied to harness, &c. In place of using the ordinary straps E and applying my guard flap H' as a protection thereto, the flap may have 60 the short straps K secured thereto and thus form itself a portion of the support or suspender.

55 What I claim as my invention is—

60 In a suspender, a buckle having the spring jaw C, the combination of the eye D, on the jaw, straps E secured to the eye and extending down at an incline in opposite directions, and a guard flap for the straps extending over and beyond the same having its upper end 70 attached to the eye and provided at its lower end with a cross strap projecting over the straps E, substantially as described.

75 In testimony whereof I affix my signature in presence of two witnesses.

JACOB CASPAR VOLLMAR.
